Primary Examiner — George D. Kirschbaum*Assistant Examiner* — Darcey E Heflin(74) *Attorney, Agent, or Firm* — Hall Estill Attorneys at Law**CLAIM**

The ornamental design for a dispenser support for deodorant or other topical product, as shown and described.

DESCRIPTION

FIG. 1 is an isometric view of a dispenser support for deodorant or other topical product showing our design in an illustrative environment.

FIG. 2 is another isometric view of the design.

FIG. 3 is a top plan view of the design.

FIG. 4 is a bottom plan view of the design.

FIG. 5 is a front side view of the design.

FIG. 6 is a rear side view of the design.

FIG. 7 is a left end view of the design.

FIG. 8 is a right end view of the design.

FIG. 9 is another isometric view of upper portions of the design; and,

FIG. 10 is another isometric view of lower portions of the design.

The broken lines in these drawings serve to illustrate the environment in which the claimed design is associated. The broken lines form no part of the claimed design.
